(57) **CLAIM**

The ornamental design for a pedal board riser, as shown and described.

DESCRIPTION

FIG. 1 is a top right rear isometric view of a pedal board riser according to my new design, where the pedal board riser is shown positioned below a pedal and on top of a pedal board; FIG. 2 is a top left rear isometric view of the pedal board riser of FIG. 1, where the pedal board riser is shown positioned below the pedal;

FIG. 3 is a bottom right front isometric view of the pedal board riser of FIGS. 1-2, where the pedal board riser is shown positioned below the pedal;

FIG. 4 is a rear elevational view of the pedal board riser of FIGS. 1-3, where the pedal board riser is shown positioned below the pedal;

FIG. 5 is a right side elevational view of the pedal board riser of FIGS. 1-4, where the pedal board riser is shown positioned below the pedal;

FIG. 6 is a left side elevational view of the pedal board riser of FIGS. 1-5, where the pedal board riser is shown positioned below the pedal;

FIG. 7 is a top plan view of the pedal board riser of FIGS. 1-6, where the pedal board riser is shown positioned below the pedal; and,

FIG. 8 is a bottom plan view of the pedal board riser of FIGS. 1-7, where the pedal board riser is shown positioned below the pedal.

The relatively thin lines are included to illustrate contour and not surface ornamentation. The appearance of any portions of the pedal board riser between the symbolic break lines shown in FIGS. 1-6 form no part of the claimed design. The broken lines shown in the various Figures illustrate portions of the pedal board riser that form no part of the claimed design.

1 Claim, 7 Drawing Sheets
